UNITED STATES PATENT OFFICE

VEGETABLE CRATE PRESS

Application March 3, 1934, Serial No. 713,928

Ulrich J. Bohnke, San Juan, Tex.

12 Claims.

This invention relates to presses and particularly to presses for use in forcing the cover on to a crate filled with vegetables and holding the cover in place while it is being nailed.

5 In the packing of vegetables in crates, it is customary to use different sizes of crates varying in height and width and it is customary in order to form a compact package of full weight to overfill the crate so that the bottom of the crate may bulge downward at its middle and the top of the crate bulge upward at its middle.

10 The general object of this invention is to provide a crate press of a character which will permit the downward bulging of the bottom and the upward bulging of the top or cover while the crate is in the press and having its cover nailed on.

15 One of the objects of the present invention is to provide a structure of this kind having rollers for supporting the crate and means for supporting a cover above the crate and provide improved means for moving the cover downward on to the crate, which means is so constructed that a fast initial downward movement is secured, and, as the cover nears the crate, the movement of the cover is slowed up but the leverage whereby the cover is forced down is greatly increased, thereby securing a great leverage at the time when it is most needed.

20 A further object is to provide means whereby the end rollers of the press bed may be raised above the level of the middle rollers so as to permit the bottom of the crate to bulge downward at the middle, thus permitting the crate to be filled more completely and giving to the filled crate a fully filled appearance which makes it more salable.

25 A further object is to provide a press of this character in which the cover supporting element is raised sufficiently from the bed as to permit the ready sliding of a crate on to the bed, the return of the end rollers to a position level with the middle rollers of the bed after the cover presser has been raised, permitting the ready movement of the crate on to the bed and off the bed.

30 A still further object is to provide improved means whereby the cover carrying member may be adjusted vertically with reference to the stroke of the machine and another object is to provide means on the cover supporting member whereby either narrow or wide covers may be used and to provide a crate guide disposed above the bed and adjustable for wide or narrow crates, this crate guide being further so constructed as to center the crate in position upon the rollers of the bed and with relation to the cover supporting element.

35 Still another object is to provide an adjustable crate cover shelf which is adjustable so as

(Cl. 100—57) to be used for either large or small covers and to provide nail spreader brackets so that the press may be used either for a right or left handed nailer or for two nailers at one press.

Other objects will appear in the course of the following description.

40 My invention is illustrated in the accompanying drawings, wherein:

Figure 1 is a front elevation of a crate press constructed in accordance with my invention, the 45 rollers being in section;

Figure 2 is a vertical section on the line 2—2 of Figure 1, the press being opened;

Figure 3 is a fragmentary section on the line 45 50 3—3 of Figure 4;

Figure 4 is a top plan view of the crate supporting table, the vertical members of the frame being shown in section;

Fig. 5 is a fragmentary section through the presser plate and the supporting members therefor showing the adjustable guide in elevation;

Fig. 6 is a fragmentary plan view of the structure shown in Fig. 5, showing the crate cover A in place within the guide, the pressure plate being indicated by dot and dash lines.

55 Referring to the drawings 10 designates angle irons extending from front to rear of the machine and constituting base skids, the angle irons being provided with runners 11 upwardly turned at their forward ends.

Extending upward from the angle irons are the two vertically disposed uprights 12 which extend the full height of the machine and opposite to these uprights 12 and at the front of the angle irons 10 are the angle iron uprights 13 which support the table frame or bed, the uprights 12 and 13 being connected by the longitudinally extending frame beams 14 at their upper ends. Carried upon these frame beams 14 are the front and rear channel irons 15 and 16.

The uprights 12 are connected and tied together by the upper spreader 17 and by the lower spreader 18, these spreaders being of angle iron. Extending between these spreaders and attached thereto are the guide rods or shafts 19 which may be circular in cross section or square in cross section as desired. Slidably mounted upon these guides 19 are sleeves 20. Extending from these sleeves 20 are the two arms 21 which support the cover presser as will be later described. The sleeves 20 are connected by the transverse angle irons 22 and between the horizontal flanges of these angle irons is disposed a sleeve 23 through which loosely passes a screw 24. This screw carries upon it the two nuts 25 and 26 which bear against the angle irons 22 and force these angle irons against the ends of the sleeve 23. By adjusting the nuts 25 and 26, the sleeve 23 and, of course, the sleeves 20 may be adjusted vertically with reference to the screw 24.

55

60

To the lower end of the screw 24 there is attached the plate 27 which in turn is connected, as will be later described, to the foot-operated depressing mechanism. The plate 27, together with the screw 24, the sleeve 28, the sleeves 20 and the arms 21 are urged to a raised position by the springs 28 which are attached at their upper ends to the angle irons 17 and at their lower ends to eyes attached to the rear edge or margin of the plate 27. Thus the cover presser which is carried by the arms 21 is normally raised.

The plate 27 is formed with the two downwardly extending ears 29 and pivoted to these ears by a pin 30 is a link 31. This link extends downward behind the channel iron 16 of the table and is pivoted at its lower end at 33 to a bell crank lever 34, this bell crank lever being mounted upon a pivot pin 35 carried by a press 36 which extends downward and rearward from the angle iron 18 and at its lower end is connected to a transverse angle iron 37 carried by the base angle irons 10. ~~See also the following description.~~

Extending upward from the base frame at the rear thereof are the ears 38 and pivoted to these ears is an operating treadle 39 in the form of a lever which extends out past the front of the press and is provided at its forward end with the treadle 40, this lever being connected to the bell crank 34 by a link 32. ~~See also the following description.~~

Extending downward from the crate supporting table to an iron 41 attached to the members 10 is a rack 42 which may be provided with one or more notches 43. Pivotedly mounted upon the lever 39 is a pawl 44 in the form of a bell crank lever, one end of this pawl being engageable with the notches 43, the other end of the pawl being urged outward by a spring 45. Thus the actuating lever may be held in a depressed position. There are two of these notches 43 so that the lever may be held depressed either for a relatively deep crate or a relatively shallow crate. A spring 46 urges the lever 39 upward. ~~See also the following description.~~

Disposed between the channel irons 15 and 16 and having their trunnions rotatable therein are the three fixed rollers 47, one of these rollers being disposed at the middle of the table. Externally of these rollers 47 are a pair of vertically movable rollers 48. Means are provided whereby these rollers 48 may be raised automatically upon a depression of the lever 39 and lowered automatically when the lever 39 is released and raised by the spring 46. To this end, the extremities of the channel irons 15 and 16 are cut away on an angle as indicated in Figure 3, the joint being designated 49. Pivoted to these angular extremities of the channel irons 15 and 16 are the channel iron sections 15^a and 16^a. Trunnioned in the ends of these sections are the rollers 48 previously referred to and thus, as these sections 15^a and 16^a move upward, the rollers will be carried upward.

For the purpose of moving the rollers upward, the trunnions of the rollers are mounted in yokes 50, these yokes being pivoted at 51 upon the same pivots as the sections 15^a and 16^a. The yokes have angular arms 52 which extend inward toward the middle of the machine.

Pivoted to the forward end of the machine beneath the table or bed and at the middle of the machine is a lever 53 whose rear end extends beyond the brace 36 and is urged upward by a spring or springs 54, the upper end of this spring being engaged with the plate 27. There may be two of these levers 53 disposed to embrace the link 32 and these simultaneously acting levers 53 are

adapted to be engaged by rollers 55. Therefore, when the link 32 is lowered by a depression of the treadle lever 39, the rollers 55 will engage the levers 53 and force these levers downward. This lever 53, or levers if two are used, is connected to a guide rod 56 which is guided in a tubular extension 57 of a shaft 58 which is oscillatably mounted in the angle irons 10. The guide rod 56 carries upon it the two arms 59 and links 60 extend from these arms to the inner ends of the levers or extensions 52 of the yokes 50. It will thus be seen that when the lever 53 is depressed by the roller 55, the bell crank levers 52 will elevate the rollers 48 as shown in Figure 3. As soon as the treadle lever 39 has been released and moves upward under the action of the spring 46 and as soon as the roller 55 moves upward, the lever 53 will move upward under the influence of the spring 54 and this will return the rollers 48 to their normal position on a level with the intermediate rollers 47.

The outwardly projecting arms 21 which are carried by the sleeves 20 carry a laterally bowed presser plate 61, this presser plate being formed with slots 62 extending inward from the side edges of the presser plate.

Attached to the presser plate 61 at its outer end is a cover guide 63 and mounted upon the presser plate 61 and extending parallel to the guide 63 is an adjustable guide 64 which carries spring cover holders 65 at opposite ends. The guide 64 is supported by angular brackets 64^a, adjustable from the position shown in full lines in Figure 2 to the position shown in dotted lines in Figure 2, by bolts 61^a passing through perforations in the presser plate 61 thus making this guide adapted to hold either narrow covers or wide covers and support the cover in position to be brought down upon the crate carried upon the rollers 47 and 48. As will be seen from Figure 2, the cover presser plate 61 is transversely curved.

Extending across the uprights 12 above the crate supporting bed or table is a crate guide 66. This is supported upon links 67 pivoted to the uprights 12. The ends of the guides 66 project laterally beyond the uprights 12 and carried upon these ends are the crate stops 68 and 69, the crate stops 69 extending outward at right angles to the crate stop 68, each of these crate stops extending outward at right angles to the guide 66 and then extending laterally and inward toward the guide 66 so that a beveled face is provided fronting toward the front of the machine when the particular stop 68 or 69 is in use. When relatively narrow crates are to be covered, the arms or links 67 extend outward at right angles to the members 12 as shown in Figure 2 and the crate stops 69 are then in use. The guide 66, under these circumstances, prevents a narrow crate from being forced rearward too far or otherwise misplaced upon the rollers 47 and 48 while the stops 69, under these circumstances, act to center the crate with its ends upon the rollers 48. When a wide crate is to be covered, the arms 67 are moved upward and the stops 68 come into use, the member 66 then acting to prevent the crate from being placed too far back upon the bed and to bring the crate in exact alignment with the cover presser 61, the stop 68 acting to center the crate, as before described.

Mounted upon the upper ends of the uprights 12 is a cover shelf 70 supported by brackets 71. To this cover shelf is attached the angular stop 72 pivoted to the shelf at 73. When this stop is adjusted as shown in full lines in Figure 2, wide covers may be disposed upon the shelf and when the stop is disposed, as shown in dotted lines, nar-

row covers will be disposed in proper position upon the shelf.

To each side of the main frame uprights 12, nail stripper brackets 74 are attached, these brackets being adapted to carry nail strippers or sorters. These nail strippers may be carried upon either or both of these brackets 74 so that the machine may be used for a right handed or left handed nailer or two nailers can work at opposite sides of the same machine. The adjustable crate shelf 70 provides a quick change shelf for large or small covers. In the position shown in full lines, it is used for holding bundles of crate covers for wide crates such as pea crates, cauliflower crates, etc. In the dotted line position, it is used for holding the covers for narrow crates, such as bushel crates, corn crates, etc.

Each of the sleeves 20 has fastened to its upper end an oil ring 75 which provides a container into which oil may be placed for oiling the guide shafts 19, thus giving the sleeves an easy action. These guide shafts 19 provide true and accurate guides for the sleeves 20 which carry the cover presser. Preferably the front ends of the beams 11 are turned upward so as to make it easier to skid the press about on the floor of a shop.

The general operation of this mechanism will be obvious from what has gone before. With the treadle lever 39 in a raised position and all of the rollers 47 and 48 disposed in a horizontal plane, a crate is placed on the rollers and rolled to a position where the ends of the crate are disposed between the inner shoulders of the stop 68 (or 69), the stop guide 66 limiting the rearward movement of the crate. With the crate in this position, the treadle 39 is then depressed and this acts through the bell crank lever 34 to depress the screw 24, the sleeve 23, the angle irons 22, the sleeves 20 and the cover presser 61. Of course, a cover has previously been placed in position between the members 63 and 64. With the crate in this position, the lever 39 is depressed, bringing the cover down upon the crate and forcing the cover into a curved shape over the crate, the rollers 48 simultaneously moving upward so that the bottom of the crate is also bulged but in an opposite direction to the cover. The cover is then nailed to the crate and when lever 39 is raised to its open position, it leaves the cover on the crate with a rounded bulge upward while the bottom of the crate is bulged downward, thus giving a very full appearance to the crate and making such filled crate more salable. When the lever 39 is released and returns to its raised position, it, of course, permits the rollers 48 to descend to the same level as the rollers 47, thus making the box table level for the removal of the cover crate and for the reception of the next crate to be covered. The crate guide 66 is quickly adjustable for wide or narrow crates while the stops on the ends of the crate guide function to center the crate properly upon the table and hold it in this centered position.

Attention is called to the action of the eccentric or bell crank lever 34. By the use of this lever, an initially fast downward movement of the cover presser 61 is secured and as the cover is depressed, the motion of the cover is slower and the leverage of the lever 34 is increased so that the greatest rapidity is secured upon the initial movement of the cover presser and the greatest leverage is secured at the time when the cover is being forced down on to the crate into position for nailing.

Furthermore, by the use of this bell crank 34

and the connecting links, the cover presser is shifted to a relatively high point or relatively great distance from the bed or table, thereby making a larger opening between the presser 61 and the roller table, allowing larger and higher vegetable packs to be placed into the press and the cover forced into place. The cover presser 61 is adjustable up or down by the adjustment screw 24 with the nuts 25 so that any height of crate may be pressed in this machine. This adjustment may be very quickly made so as to suit the machine to different sized crates.

While I have illustrated certain details of construction and arrangements of parts, it will be understood that many minor changes might be made in the details without departing from the spirit of the invention as defined in the appended claims.

I claim:

1. In a crate press, a frame, a crate supporting table carried thereby, the frame having uprights extending above the crate supporting table, a vertical guide mounted upon the frame, an element slidably mounted upon said guide, a pressing member carried by said sliding element and extending over the pressing table, a vertically movable member mounted upon the frame, manually operable means for reciprocating said member vertically, a screw carried by said member, a sleeve attached to the guide and through which the screw passes, and nuts engaging said screw on either end of the sleeve whereby the sleeve may be adjusted vertically upon the screw and with relation to the manually operable means to thus adjust the initial height of the pressing member with reference to the table.

2. In a crate press, a frame, a crate supporting table mounted on the frame, the frame having vertical members extending above the table, a pair of guides mounted upon the upwardly extending portion of the table, sleeves mounted upon said guides for vertical reciprocation, arms extending outwardly from the sleeves at the upper ends thereof, a cover pressing element carried by said arms above the table, transversely extending angle irons carried by the sleeves, a medially disposed sleeve mounted between said angle irons, a cross head disposed between the guides, a manually depressible treadle operatively connected to the cross head, springs urging the cross head upward, a screw mounted on the cross head and extending upward therefrom parallel to the guides, the screw passing through said second-named sleeve, and nuts engaging the transverse irons and engaging against the upper and lower ends of said last named sleeves to thus permit the first and second named sleeves to be unitarily adjusted vertically with reference to the cross head.

3. In a crate press, a frame, a crate supporting table, a pressing element mounted on the frame for vertical reciprocation, and manually controlled means for vertically reciprocating the pressing element toward or from the table, the pressing element being transversely bowed and having nailing slots, the outer margin of the pressing element having a downwardly depending cover engaging member, the inner portion of the pressing element having a downwardly extending cover engaging element, the last named element being adjustable toward or from the first named element, and resilient means for engaging a cover with the under side of the pressing element.

4. In a crate press, a crate supporting table having end rollers and intermediate rollers, all of the rollers being disposed normally in a horizontal plane, a cover supporting pressing element 5 mounted above the crate supporting table for movement toward the crate supporting table, means for depressing the pressing element, and means acting upon the depression of the pressing element to raise the end rollers to a level 10 above the intermediate rollers.
5. In a crate press, a frame, a crate supporting table carried thereby, a pressing element mounted on the frame for vertical reciprocation, the pressing element being bowed transversely of the frame, manually operable means 15 for vertically reciprocating the pressing element, end rollers mounted upon the table for vertical movement, intermediate rollers mounted upon the table, all of said rollers being disposed normally in a horizontal plane, and means acting 20 upon the depression of the cover supporting pressing element to raise the end rollers above the intermediate rollers whereby the bottom of the crate may be bowed downward at its middle.
6. In a crate press, a frame, a cover supporting 25 pressing element mounted on the frame for vertical reciprocation, manually operable means for vertically reciprocating the pressing element and including a treadle lever normally urged upward, a crate supporting table disposed below the pressing element and having end rollers and medial rollers, all of said rollers being disposed initially in a horizontal plane, levers carrying 30 the end rollers, both of said levers being operatively connected to a vertically movable element disposed in the path of movement of the treadle lever when the latter is depressed whereby as 35 the treadle lever is depressed, the lateral rollers are raised above the medial rollers.
7. In a crate press, a frame, a cover supporting 40 pressing element mounted on the frame for vertical reciprocation, manually operable means for vertically reciprocating the pressing element and including a treadle lever pivoted at one end, the treadle lever being urged to a raised position, a crate supporting table disposed beneath the 45 pressing element and including opposed parallel supporting irons, the ends of said irons having vertically movable sections, end rollers carried by the vertically movable sections of the iron, intermediate 50 rollers carried by the fixed sections of the irons, and means for raising the end sections of the irons and said end rollers including levers carrying said rollers and pivoted intermediate 55 their ends, a vertically depressible member to which the inner ends of said levers are both connected, the depressible member being disposed in the path of movement of and operatively engaged by the treadle when the latter is depressed to thereby 60 raise the end rollers.
8. In a crate press, a frame, a cover supporting 65 pressing element mounted on the frame for vertical reciprocation, manually operable means for vertically reciprocating the pressing element and including a treadle lever pivoted at one end, the treadle lever being urged to a raised position, a crate supporting table disposed beneath the pressing element and including opposed parallel supporting irons, the ends of said irons having vertically 70 movable sections, end rollers carried by the vertically movable sections of the iron, intermediate rollers carried by the fixed sections of the irons, and means for raising the end sections of
- the irons and said end rollers including levers carrying said rollers and pivoted intermediate their ends, a vertically depressible member to which the inner ends of said levers are both connected, the depressible member being disposed in the path of movement of and operatively engaged by the treadle when the latter is depressed, the vertically 5 depressible element including a vertical rod, and a tubular guide for the rod, the tubular guide being mounted on the frame for oscillation at right angles to the plane of movement of the roller carrying levers.
9. In a crate press, a supporting frame, a crate supporting table, a cover supporting pressing element mounted on the frame for vertical reciprocation, means for vertically reciprocating the press element toward or from the table, a crate guide extending across the frame above the table, and arms pivoted to the frame and carrying the crate guide, said arms being movable into a position at right angles to the frame and extending over the table or into a vertical position with the crate guide disposed closely adjacent the frame.
10. In a crate press, a supporting frame, a crate supporting table, a cover supporting pressing element 25 mounted on the frame for vertical reciprocation, means for vertically reciprocating the press element toward or from the table, a crate guide extending across the frame above the table, and arms pivoted to the frame and carrying the 30 crate guide, said arms being movable into a position at right angles to the frame and extending over the table or into a vertical position with the crate guide disposed closely adjacent the frame, said 35 crate guide having a length greater than the table, and stops mounted upon the crate guide and operative in either position of the crate guide, said stops projecting outward from the crate guide to provide means for centering a crate upon the table.
11. In a crate press, a supporting frame, a crate supporting table, a reciprocatable pressing element mounted upon the table and a cover supporting shelf carried upon the upper end of the frame and extending rearwardly and then upwardly, and connected angular elements pivotally 45 mounted upon the rearwardly extending portion of the shelf, the pivoted portion of the elements having a length equal to the rearwardly extending portion of the shelf and being pivoted to the shelf inwardly of the upwardly extending portion whereby in one position the members constitute 50 stops limiting the depth of the cover supporting shelf and, in another position, being disposed within the lines of the cover supporting shelf.
12. In a crate press, a frame, a crate supporting table carried thereby, the frame having uprights extending above the crate supporting table, an element mounted upon said frame for vertical sliding movement, a pressing member carried by 55 said element and extending over the pressing table, a vertically movable member mounted upon the frame, means for reciprocating said member vertically, and means connecting the sliding element to said member and including a relatively long screw operatively connected to the member and extending up therefrom, and a sleeve connected to the sliding element and through which said screw passes, the sleeve being vertically 60 adjustable upon the screw and adjustably engaged therewith to thus adjust the initial height of the pressing member with reference to the table.
- ULRICH J. BOEHNKE.
